UNITED STATES PATENT OFFICE.

WILLIAM RILEY MONTGOMERY, OF LOUISVILLE, KENTUCKY, ASSIGNOR OF
ONE-HALF TO THOMAS H. MONTGOMERY, OF CHICAGO, ILLINOIS.

PLUG-MACHINE.

SPECIFICATION forming part of Letters Patent No. 727,666, dated May 12, 1903.

Application filed October 26, 1900. Serial No. 34,467. (No model.)

To all whom it may concern:

Be it known that I, WILLIAM RILEY MONTGOMERY, a citizen of the United States of America, residing in the city of Louisville, in the county of Jefferson and State of Kentucky, have invented certain new and useful Improvements in Plug-Machines, of which the following, taken in connection with the accompanying drawings, is a specification.

This invention relates to mechanism for both forming and finishing plugs or briquets without the necessity of putting them through separate mechanisms for the several purposes. While it is clearly usable in connection with any substance which it is desired to treat in this manner, I have designed it for special use in connection with the formation of tobacco-plugs. Heretofore it has been customary in mechanism of this class to form the tobacco-plug in a press, one plug at a time, and then eject the same from the mold or former, to be afterward placed in a receptacle of some suitable shape, there to be held for some period of time in order that the plug might retain the shape given it in the mold.

The first of the objects of my invention is to reduce the mechanism required for finishing or forming plugs or briquets by providing a machine in which both the compressing or forming and the finishing operations can be done without passing the material through other machines.

In carrying out my invention I secure more economical results than have been heretofore possible and secure other advantages which will be hereinafter more apparent.

In the annexed drawings, which illustrate a machine embodying my invention in preferred form, Figure 1 shows the mechanism 40 in side elevation, and Fig. 2 another view in elevation, a portion of it being taken in section upon line 2 2 of Fig. 1. Fig. 3 is a partial view showing some of the details in vertical section. Fig. 4 is another view, also 45 partly in section, showing the clamping devices which I employ. Fig. 5 is a plan section on the line 5 5 of Fig. 4. Fig. 6 is a plan view of the bed of the machine, and Fig. 7 is a detail section showing the clamping mechanism used in connection with part of my device.

Referring, in the first place, more particularly to Figs. 1 and 2, it will be seen that in carrying out my invention I provide, first, a frame or support for the machine 1, carrying 55 a bed 2 at its lower part and a reciprocating plunger 3 at its upper portion, coupled with mechanism comprising, essentially, a pitman 4 and the gears 5 and belt-wheel 6 for imparting reciprocation to the plunger 3. Upon the bed 2 is provided a box 7, having removable sides 8 and reinforcing portions 9, held together by means of clamp devices, such as the wedges 10, and, as shown in Figs. 3, 4, and 5, carrying within the sides a plunger or 60 receding bottom 11, supported upon a rod 12, which is pressed between two clamps 13, held against the rod, by means of the screw or clamping device 14 in such a manner as to resist compression of the material placed within 65 the machine and at the same time to recede sufficiently to make room for each plug as it is formed. The upper end of the box is provided with a removable flask or frame 15, designed for measuring the quantity of material to be put in one plug, and there are also provided upon the upper end of the box a couple of hasps 16, pivoted to the box in such a manner that when the flask 15 is removed after the box is filled with plugs the hasps 16 70 can be swung upwardly into position, as shown in Fig. 4, and a couple of keys or wedges 17, driven in to hold down a cover 18, put in place, and thus retain the plugs in the box, which may then be taken off the machine and kept as long as is necessary to insure the plugs retaining their proper shape 75 permanently. Around the sides or ends of the box are a couple of straps 19, designed to aid in holding the parts together, and at 80 20 are arranged some dowel-holes designed to receive dowel-pins fixed in the side portions of the box, so as to insure their being put together in proper position. The bed of the box 2 is composed of two parts held together 85 by means of the bolts 21 in the manner clearly shown in Fig. 6, and the screw device 14 has a handle for operating the same (shown at 22) and can by means of this be readily adjusted to secure any desired degree of pressure upon 90 the rod 12 that may be desired.

The rod 12 is preferably made tubular and

provided upon the inside with an inner rod 23, carried by means of a foot-lever mechanism 24, by which pressure with the foot will cause the rod 23 and the plunger 11, carried 5 thereupon, to be lifted.

The operation of my invention is as follows: The plunger 11 having been raised to position even with the top of the box and the flask or frame 15 having been put in place 10 with the compressing-plunger 3 elevated to its highest position, the flask 15 is filled with the material to be compressed and the plunger 3 then caused to move downward and compressing the material in the flask until it 15 is squeezed into the box, at the upper portion thereof, the plunger 11 having during the compressing operation exerted a resistance due to the friction upon the rod 12, but also having receded a sufficient distance to make 20 room for the plug as it is formed, as is indicated at 24 in Fig. 2. A small separator or plate 26 is then put upon the finished plug, and another lot of material having been put into the flask 15 this is compressed, the plunger 11 receding another step and permitting 25 the formation of another plug. In this manner plugs may be formed successively, one on top of another, until the entire box is filled, after which the top 18 is placed upon it and 30 the wedges 17 driven in to hold the top in place and the box taken off the machine to permit another box to be put in place of it for the formation of another lot of plugs.

From the above it is obvious that by providing a sufficient number of boxes 7 the machine can be operated practically continuously and the tobacco after it is formed into 35 plugs retained in the boxes until it is certain to keep its proper shape, when the boxes can 40 be taken apart and the tobacco taken out.

Having thus described my invention, what I claim as new, and desire to secure by Letters Patent, is—

1. A machine for forming and finishing 45 plugs of tobacco, comprising a reciprocating compressing-plunger, means for operating the

same, a removable box wherein to compress the plugs, a resisting-plunger within said box, and means whereby to impart a predetermined degree of resistance to said resisting- 50 plunger, and to permit a step-by-step recession thereof within said box, during the operation of said compressing-plunger, substantially as described.

2. A machine for forming and finishing 55 plugs or briquets comprising a reciprocating compressing-plunger, means for operating the same, a box wherein to compress the plugs, a resisting and receding plunger within said box, and clamp devices for permitting 60 an intermittent recession under fixed pressure, of said plunger, substantially as described.

3. A machine for forming and finishing 65 plugs or briquets comprising a reciprocating compressing-plunger, means for operating the same, a removable box wherein to compress the plugs, a resisting and receding plunger within said box, a rod supporting 70 said receding and resisting plunger, and friction devices bearing upon said rod, whereby to govern the resistance of the same and the extent to which it recedes, substantially as described.

4. A machine for forming and finishing 75 plugs or briquets comprising a reciprocating compressing-plunger, means for operating the same, a removable box wherein to compress the plugs, a bed whereupon said box may rest, a resisting and receding plunger within said box, a rod supporting said plunger and passing through said bed, and clamp devices for exerting friction upon said rod, substantially as described.

In testimony whereof I have hereunto set 85 my hand in the presence of two subscribing witnesses.

WILLIAM RILEY MONTGOMERY.
